STITCH REMOVING TOOL

Benjamin Franklin Rhodes, Eufaula, Ala., assignor of one-third to Hubert E. James, one-third to William Alton Clifton, and one-third to Herbert L. Clifton, all of Eufaula, Ala.

Application June 1, 1936, Serial No. 82,977

4 Claims. (Cl. 12—103)

This invention relates to stitch removing tools, and particularly to means for displacing remnants of stitches that are left in the welt of a shoe or middle sole thereof when the stitches have been cut for the removal of the worn sole of a shoe. In order to afford a neat and satisfactory repair job, the remnants of stitches remaining in the needle holes of welts or middle soles should be removed and, to that end, novel means are provided for displacing such remnants of thread preparatory to resoling of a shoe.

It is an object of this invention to provide a novel thread displacing instrumentality which can be expeditiously manipulated for accomplishing the result, and the invention furthermore provides means for displacing threads that may accumulate on the thread removing teeth or spurs of the thread displacing instrumentality.

It is furthermore an object of this invention to provide novel means for operating the thread displacing device, all of which is associated with the head and handle of the tool.

It is still further an object of this invention to provide means for guiding the thread removing spurs with relation to the rows of threads or stitching of the welt or middle sole and, as a further improvement, to provide novel means for regulating or adjusting the guiding means with relation to the thread displacing instrumentality.

With the foregoing and other objects in view, the invention consists in the details of construction, and in the arrangement and combination of parts to be hereinafter more fully set forth and claimed.

In describing the invention in detail, reference will be had to the accompanying drawing forming part of this application, wherein like characters denote corresponding parts in the several views, and in which—

Figure 1 illustrates a view in elevation of a tool embodying the invention, the face plate of which is removed;

Figure 2 illustrates a view in elevation of the opposite side of the tool;

Figure 3 illustrates a detail view of the thread removing teeth or spurs and the means associated therewith for displacing threads accumulated thereon; it being a section taken on the line 3—3 of Fig. 2;

Fig. 3a illustrates a view in elevation of a fragment of a shoe with a fragment of the device embodying the invention in position for operation;

Figure 4 illustrates a detail view of a modification of the tool guiding means;

Figure 5 illustrates a side view thereof;

Figure 6 illustrates a plan view of a further modified construction; and

Figure 7 illustrates a view of a further modification.

In these drawings the tool is illustrated as embodying a handle 10 and an integral hollow housing 11, including a head 12, in which the operating parts of the mechanism are encased.

The outer surface of the head is provided with a plate 13 with teeth or spurs 14 thereon, occupying spaces at the marginal edge of the said plate. The plate may be secured to the head by any appropriate means, as by fastenings 15, in the nature of screws, rivets or the like.

The head and plate have coinciding apertures 16 through which a rod or plunger 17 reciprocates, and the upper wall of the said head has an aperture 18 in which the plunger is guided during its manipulation, as will presently appear. The plunger has a guide 19 secured to its side, which guide is integral with a plate 20 having recesses or slots 21 that receive the teeth or spurs, it being understood that the plate reciprocates longitudinally of the spurs. Normally the plate is located at the bases of the spurs, and during the manipulation of the stitch removing tool, the said plate remains in contact with the plate 13, but when the plunger is reciprocated, the plate is moved along the teeth or spurs and dislodges threads that may accumulate on the said teeth or spurs during the manipulation of the tool. The plunger is operated by a lever 22 extending longitudinally of the housing and connected to the plunger by a pivot 23 which may be a screw anchored to the plunger and extending through a slot 24 of the said lever. It is shown in the drawing that the lever is angularly disposed and that a depending portion 25 thereof extends through a slot 26 in the bottom of the housing and said lever terminates in an extension 27 forming a finger grip, by which the lever and the parts associated with it are manipulated. It is shown that the housing has lugs 28 and 29 spaced the distance of the width of the slot, or approximately so, and that a pivot 30 extends through the said lugs and the space therebetween on which the lever is mounted.

The plunger is held retracted, that is to say, in the normal position shown in Fig. 1, by a spring 31 which has one end anchored to the inner wall of the housing and its other end bearing against the under side of the lever in

proximity to its connection with the plunger. A suitable face plate 32 is applied to the housing by fastenings 33 such as screws.

The guide is, of course, intended to engage the edge of the welt and, when in such engagement, the teeth or spurs will register with the line of needle holes in the welt but, under some conditions, the space between the edge of the welt and the needle holes varies to a degree which might render the tool ineffective if the space between the guide and teeth were fixed. The guide 19, in this form of the invention, may be adjusted with relation to the teeth by having a slot or clearance 13^a that permits movement of the plunger 17 laterally of the head, and the plunger is held at different positions of adjustment by a screw 13^b threaded in the head, as shown. A spring 13^c bears against the side of the plunger opposite that engaged by the screw, so that the said plunger is held in different positions of adjustment against movement other than that imparted to it by pressure of the guide on the work or the movement imparted to the said plunger by the adjustment of the screw.

In order to provide means for adjusting the position of the guide with relation to the edge of the plate which it carries and with relation to the teeth, the embodiment shown in Figures 4 and 5 may be adopted and in that construction the plate 34 may be provided with a stationary flange 35 at its edge, threaded to receive a screw 36 and the screw is swivelled in the guide 37 so that when the screw is adjusted in the flange, it will move the guide with relation to the edge of the plate which receives the teeth or spurs.

A further modification of a guiding means is found in Figure 6, in which the plate 38 that is intended to engage the teeth has an eccentric guide 39 secured on a stud 40 and, by this means, the eccentric guide may be turned to different positions so that its periphery will be near or remote from the edge, according to the distance between the edge of the welt and the row of stitches which it is desired to remove.

In the modification shown in Figure 7, the guiding means for the plate 41 comprises a curved spring 42 having its ends anchored to the plate as at 43 and 44 by suitable fastenings, such as pins. The convex side of the spring faces the edge of the plate having the teeth and, in the use of the tool of this modification, pressure would be exerted by the operator to locate the teeth of the tool in alignment with the stitch openings when the said spring engaged the edges of the welt, acting as a guide for the tool.

As shown in Fig. 3a, the fragment of the shoe A has a sole or welt B with relation to the stitches C of which the tool is in operative relation.

When it is desired to manipulate the tool with relation to the stitches of a sole of a shoe, the guide 19 is caused to engage the edge of the sole or welt and the relation of parts is such that when proper adjustment is made, the spurs 14 are in line with the severed threads of the stitching and when the tool is manipulated the said threads are dislodged. If the threads adhere to the spurs, they are dislodged by moving the plunger longitudinally and this carries the plate 20 having the recesses or slots 21 so that the said plate passes longitudinally of the spurs and forces the threads therefrom, as shown in dotted lines, Fig. 3. The plunger is moved by the manipulating instrumentalities heretofore described and it returns to its normal position under the influence

of springs supplied for that purpose. The stitches in the shoe extend longitudinally of the welt and the tool is moved along the welt with the spurs 14 in line with the stitching and as the said tool is reciprocated transversely of the welt, the spurs engage the threads and displace them or pull them out of the thread holes. In Fig. 3 the threads are shown as extending transversely of the spurs but that is only a conventional illustration for, as a matter of fact, the threads will be fibrous or broken up to such an extent that they will appear more like a bunch of cotton which will be displaced by the manipulation of the plate 20 in the manner described.

I claim:

1. A stitch removing tool comprising a handle and a housing integral therewith, said housing having a hollow head whose upper and lower walls are provided with alining apertures, a plate on the outer surface of the head having an aperture alining with the apertures of the head, alined stitch removing teeth on the said plate, a plunger slidable in the said apertures and projecting beyond the plate, a guide secured to the said projecting part of the plunger, said guide having a thread removing plate with recesses to receive the aforesaid teeth, and means for reciprocating the plunger for moving the thread removing plate longitudinally of the teeth.

2. A stitch removing tool comprising a handle and a housing integral therewith, said housing having a hollow head whose upper and lower walls are provided with alining apertures, a plate on the outer surface of the head having an aperture alining with the apertures of the head, alined stitch removing teeth on the said plate, a plunger slidable in the said apertures and projecting beyond the plate, a guide secured to the said projecting part of the plunger, a thread removing plate carried by the guide, said plate being in engagement with the aforesaid teeth, and means for reciprocating the plunger for moving the guide and the said plate longitudinally of the teeth.

3. A stitch removing tool comprising a handle and a housing integral therewith, said housing having a hollow head whose upper and lower walls are provided with alining apertures, a plate on the outer surface of the head having an aperture alining with the apertures of the head, alined stitch removing teeth on the said plate, a plunger slidable in the said apertures and projecting beyond the plate, a guide secured to the said projecting part of the plunger, a thread removing plate carried by the guide, a lever pivotally mounted in the housing having an end pivotally connected to the plunger, said lever projecting beyond the housing and terminating in a finger grip by which the lever is manipulated, and a spring anchored to the inner wall of the housing and bearing against said lever to retract the plunger.

4. A stitch removing tool comprising a handle and a head apertured to form guides, a plate on the end of the head having stitch removing teeth, a plunger slidable in the guides of the head and projecting beyond the plate, a guide secured to the plunger and operative to engage the edges of welts of shoes, a lever pivotally mounted on the structure and operative to reciprocate the plunger, and a yieldable means for returning the plunger to normal position.

BENJAMIN FRANKLIN RHODES.
